UNITED STATES PATENT OFFICE.

THOMAS MILNE, OF SANDON, CANADA.

SCAFFOLD OR PORTABLE TRESTLE.

SPECIFICATION forming part of Letters Patent No. 643,969, dated February 20, 1900.

Application filed October 4, 1899. Serial No. 732,499. (No model.)

To all whom it may concern:

Be it known that I, THOMAS MILNE, a subject of the Queen of Great Britain, residing at Sandon, in the Province of British Columbia 5 and Dominion of Canada, have made certain new and useful Improvements in Scaffolds or Portable Trestles, of which the following is a specification.

My invention is an improvement in that 10 class of extension or adjustable scaffolds or portable trestles which are practically designed and adapted for the use of carpenters, plasterers, house-painters, paper-hangers, bricklayers, and other mechanics and workmen whose requirements of work are more or 15 less similar.

My scaffold or trestle is adapted for adjustment, and hence for extension or contraction, vertically and horizontally, as conditions require.

A special feature of the invention is the adaptation of the parts of the trestle for detachment, and another is the provision and 25 peculiar construction of metal castings for holding or supporting and connecting the different wooden portions or bars composing the frame proper of the scaffold or trestle.

Still other features are the arrangement of the bars relative to each other and the provision and application of special castings for 30 holding planks or boards which may be laid on the scaffold or trestle.

The details of construction and arrangement of parts are as hereinafter described 35 and claimed.

In the accompanying drawings, Figure 1 is an end view of my improved scaffold or trestle. Fig. 2 includes two perspective views of a metal casting which connects certain wooden 40 parts of the trestle. Fig. 3 is a side view of the trestle. Fig. 4 is a plan view. Fig. 5 is a perspective view of a metal casting which connects upper wooden portions of the trestle. Fig. 6 is a perspective view of an attachment 45 consisting of a special casting for holding planks or boards on the trestle proper.

The scaffold or trestle is composed of two 50 duplicate parts or structures A and A', which are in practice arranged parallel a suitable distance apart, as shown in Fig. 1. The base portion of each of the parts A and A' consists (see Fig. 1) of two sets of pairs of legs 1, con-

necting-bars 2 and 3, and a metal casting 4. The legs are set at an acute angle to each other, and their convergent upper ends are 55 detachably connected by the casting 4, the same being provided with sockets or pockets adapted to receive the pointed or wedge-shaped ends of said legs, as shown. Screws 5 are employed to secure the parts together. 60 The metal brace and cross-bar 3 has a guide opening or keeper 6 (see Fig. 2) for reception of the vertical bars 7, forming part of the top of the trestle. Such keeper-bars 3 are secured to the legs 1 by screw-bolts, as shown. 65 The aforesaid castings 4 have transverse slots 8 to receive a wooden bar 9, that constitutes the top of each base section or half A or A' of the trestle. These bars 9 are adapted to slide in said slots 8 and may hence be easily inserted or removed.

It is apparent that boards or planking may be laid and supported upon the bars 9 of two such trestle bases or sections when a low trestle is required.

The upper extensible portion of the trestle is formed of the aforesaid vertical rods 7, transverse bars 10, (see Fig. 3,) and castings 11, which are applied to and connect the ends of said rods 7 and bars 10—that is to say, the 80 bars 10 are adapted to enter and slide in horizontal slots 12 (see Fig. 5) in said castings 11, while the rods 7 enter sockets 13 in the same and are held detachably therein by means of screws 14. The said rods may be 85 slid up or down in the guides 6 of the lower castings 4, Fig. 2, and also through the guides or keepers 15, (see Figs. 1 and 3,) formed on the cross-bars 3, connecting the legs 1 of the trestle-bases. The rods 7 may be slid up or 90 down in these guides 6 and 15, as required for adjusting the height of the trestle, and are secured and held in any adjustment by means of stout pins 16, which are inserted in transverse holes in the rods 7 and rest upon 95 the castings 4, as shown.

Planks or boards are laid upon the opposite top bars 10 of the trestle, as shown in Fig. 1, and they may also be laid upon the lower cross-bars 9 in the same manner.

For the purpose of preventing the planks slipping, especially when one is laid upon and parallel to a bar 10, as may be required to extend the width of the trestle, I propose to

employ the special metal casting shown in Fig. 6, the same having a straight top portion, provided with points 17, and having parallel pendent base-flanges 18, which receive the bar 10 between them. This saddle-like casting may obviously be easily set in place or removed, as the case may be.

The adaptation of my improved trestle or scaffold for extension and for detachment of its parts is a particularly valuable feature. The latter enables it to be packed and transported in small space and to be carried through tunnels or other passages too narrow to permit entrance of the complete structure.

15 The whole design is intended to admit of construction in wood or metal, as may be considered most suitable.

What I claim is—

1. The improved trestle composed of two castings 4, having sockets in the under side, transverse slots and vertical slots, and the two sets of divergent legs fitted in said sockets, horizontal bars 9, which are adjustable

in the transverse slots, and vertical bars which are adjustable in the vertical slots, castings 25 11 applied to such vertical rods, and having sockets and transverse slots, and the horizontal top connecting-bars 10, as shown and described.

2. The improved trestle composed of the 30 castings 4 having leg-sockets, transverse slots, and vertical slots arranged exteriorly to said sockets, the divergent legs 1, horizontal bars 9, and vertical rods 7, passing through the vertical slots, and devices secured to the legs 35 for holding and guiding the lower portions of said rods, as shown and described.

3. As an improved article of manufacture, the castings 4 having vertical slots 6, leg-sockets in the under side, and transverse 40 slots 8 arranged between the said sockets and vertical slots, as shown and described.

THOMAS MILNE.
